UNITED STATES PATENT OFFICE.

ALPHA O. VERY, OF SPRINGFIELD, MASSACHUSETTS.

STARTING DEVICE FOR INTERNAL-COMBUSTION ENGINES.

SPECIFICATION forming part of Letters Patent No. 681,523, dated August 27, 1901.

Application filed January 25, 1901. Serial No. 44,664. (No model.)

To all whom it may concern:

Be it known that I, ALPHA O. VERY, a citizen of the United States of America, residing at Springfield, in the county of Hampden and State of Massachusetts, have invented new and useful Improvements in Starting Devices for Internal-Combustion Engines, of which the following is a specification.

This invention relates to internal-explosion engines, and pertains particularly to starting devices for engines of this class.

It is well known that in engines of this class to start them it is necessary to give to the crank-shaft a few revolutions in order to draw in a charge of explosive mixture and to explode the same to set up the automatic movements of the machine. This is usually done by means of a crank fitted on the end of the crank-shaft and turned by hand. When these engines are applied to motor-vehicles, this operation necessitates the starting of the motor before mounting the vehicle, or if the motor is stopped for any cause when the vehicle is moving then the operator must get out of the wagon and apply the crank, as stated, to start up again.

The object of this invention is to provide means for starting the motor when the operator is on the seat and therefore in position to control the vehicle; and it consists in the construction set forth in the following specification and clearly pointed out in the claims.

In the drawings forming part of this specification, Figure 1 is a side elevation of a motor-vehicle having my invention applied thereto. Fig. 2 is a sectional elevation of a spring ratchet-drum secured to the crank-shaft of the motor. Fig. 3 is an end elevation of the same, partly broken away. Figs. 2 and 3 are shown of substantially the natural size of the parts.

In carrying out my invention I apply a spring ratchet-drum to the crank-shaft of the engine, and around this drum I apply a chain, one end of which is attached to the drum and the free end of which is secured to the wagon-body, and a lever extending up within reach of the operator has an engagement with this chain when the lever is operated, whereby by means of the latter said ratchet-drum may ro-

tate the crank-shaft of the engine, the spring in the drum swinging the operating-lever back to normal position again when the lever is released. These various devices are constructed as follows:

The ratchet-drum is constructed by applying an annular cup-shaped piece *a* over the end of the crank-shaft *b* of the motor, a portion of the latter being indicated by *c*. Said piece *a* is loose on the crank-shaft and is secured to the motor by screws, as shown, or otherwise. The ratchet member *d* is provided with a hub *e*, which extends into said piece *a*. This ratchet member is secured to the crank-shaft *b* by a set-screw or other suitable means. On the hub *e* of the ratchet member there is mounted the sprocket-wheel *f*, whose hub likewise projects into said cup-shaped piece *a*. This construction provides for an annular space inside of the member *a* for a coiled spring *g*, the outer end of which is made fast to the piece *a* and the other end of which is secured to the hub of the sprocket-wheel, all as shown in Fig. 2. On the ratchet member *d* the teeth *h* are provided, which are shown clearly in Fig. 3, these teeth lying under a flange *i* on the sprocket-wheel. The teeth are cut with rather long inclines, which, together with the flange *i*, form tapering pockets, in each of which is placed a steel roller *k*, constituting a well-known form of clutch. A sprocket-chain *l* has one end thereof secured to a tooth of the wheel *f*, and said chain after encircling said sprocket has its free end secured to the wagon-body, as at *m*, Fig. 1. This chain is of such length as to permit it to be looped over a small sprocket-wheel *n*, as shown in Fig. 1, which is carried on the lower end of a lever *o*, pivotally supported at any convenient point, as *p*, in the body of the wagon. Preferably the lever is so bent as to conform to the forward end of the body, as shown in Fig. 1, whereby when it is in its position of rest it will be out of the way. This lever, preferably, is located on that side of the wagon-body on which the chain is located, but not necessarily, for the said pivot-pin *p* may take the form of a rod, if desired, running transversely of the wagon-body, on one end of which rod the chain-engaging end of the lever *o* could be secured and on the op-

- posite end thereof the handle end of said lever. In practice instead of a sprocket-wheel *f* the chain may be applied to a drum, whereby the chain may be given more than one 5 turn spirally around the drum. Ordinarily, however, the sprocket construction shown herein may be made of such diameter as will impart the necessary rotation to the crank-shaft of the motor.
- 10 In the end of the ratchet member *d* a notch *q* is provided, whereby the engine may be given the necessary rotative impulses by means of a crank applied to the crank-shaft and engaging by means of a suitable projection 15 thereon said notch *q*. It will be observed that the rotations may be imparted to the crank-shaft manually by means of a crank, as described, or by means of the chain *l* and lever *o* independently one of the other.
- 20 From the above description of the starting device it will be seen that very convenient means are afforded for imparting the initial rotation to an internal-combustion engine for starting the same and that by means of the 25 spring-drum and an operating-lever engaging a loop of the chain, as shown, it gives a very powerful and elastic connection with the motor easily accessible to and easily operated by a person on the seat of the vehicle.
- 30 While a specific form of spring ratchet-drum has been described herein, I do not confine myself to this particular construction, for it is obvious that other forms of ratchet-

drums of this nature could readily be substituted therefor.

Having thus described my invention, what I claim, and desire to secure by Letters Patent of the United States, is—

1. The combination with the crank-shaft of an explosion-engine, of a ratchet-drum on said shaft, a flexible member secured by one end to the drum and passing therearound, and fixedly secured by its opposite end; a pivotally-supported lever engaging said flexible member between its ends, whereby the swinging of the lever will rotate said drum and crank-shaft, in one direction, substantially as described. 40
2. In a motor-vehicle provided with an explosion - engine, the combination with the 45 crank-shaft of the engine, of a pivotally-supported lever located in proximity to the seat of the vehicle, a spring ratchet-drum on said crank-shaft for rotating it in one direction, a sprocket-chain encircling the drum and attached thereto by one end, and having its opposite end attached to the vehicle, a sprocket-wheel on one end of said lever and engaging said chain, whereby the swinging of said lever will rotate said drum and crank-shaft, 50 substantially as described. 55
